UNITED STATES PATENT OFFICE.

OSCAR E. WORMAN, OF MINNEAPOLIS, MINNESOTA.

ARTIFICIAL LIMB.

1,383,365.

Specification of Letters Patent.

Patented July 5, 1921.

Application filed March 8, 1920. Serial No. 364,083.

To all whom it may concern:

Be it known that I, OSCAR E. WORMAN, a citizen of the United States, residing at Minneapolis, in the county of Hennepin and 5 State of Minnesota, have invented certain new and useful Improvements in Artificial Limbs, of which the following is a specification.

My invention relates to artificial limbs 10 and more particularly to artificial limb members for use in cases of amputation below the knee. An object of my invention is to provide an artificial limb which will not only resemble the corresponding human 15 limb in shape, but will function in a manner similar thereto so that persons who have been crippled by the loss of lower limbs may have their usefulness restored while, at the same time, the handicap in appearance which 20 would otherwise exist is overcome. Another object is to provide an artificial limb which may be readily and economically manufactured and which will insure a maximum amount of comfort to the individual 25 wearing the same.

The full objects and advantages of my invention will appear in connection with the detailed description and the novel features embodied in my inventive idea will be 30 particularly pointed out in the claims.

In the accompanying drawings which illustrate my invention embodied in an artificial limb intended for use in cases of amputation below the knee:

35 Figure 1 is a view in side elevation showing particularly the knee-joint construction. Fig. 2 is a view on an enlarged scale similar to Fig. 1 but showing the knee joint in its bent position. Fig. 3 is a view in section on the line 3—3 of Fig. 2. Fig. 4 is a sectional view showing one manner of supporting the slip-socket. Fig. 5 is a view partly in section and partly in side elevation, showing another manner of supporting the slip-socket. Fig. 6 is a detailed view, partly in section. Fig. 7 is a sectional view at right angles to Fig. 6. Fig. 8 is a view mostly in side elevation of a modified construction for use in cases of amputation below the knee. Fig. 9 is a detailed view looking at the rear upper portion of the shank member shown in Fig. 8. Fig. 10 is a view in section on the line 10—10 of Fig. 8. Fig. 11 is a view in section on the line

11—11 of Fig. 8. Figs. 12 to 15 are detail views. Fig. 16 is a sectional detail view of the ankle joint construction.

Referring to the particular construction shown in the drawings which illustrate the principles of my invention and the construction of which may be varied in regard to mechanical details without departing from the spirit of the invention, the character 14 designates a shank member which may be properly shaped from a hollow or tubular 65 shell member made from fiber, rubber, aluminum or any molded material constructed with or without seams and which may be made in standard or stock sizes to be cut off and completed as needed according to the 70 character of the amputation. The shank member, as shown in Figs. 1 to 5 is provided with a slip-socket 16, supported for sliding movement in the upper end thereof. The shank member is pivotally connected 75 to an upper leg member or lacer 18 by a knee-joint formed by upper knee-joint straps 20 and lower knee joint straps 22 pivoted to each other by a knee bolt 24. As shown in Fig. 4, the knee-joint strap 22 may 80 be provided with a shoulder or offset 26 to rest upon the top of the shank member. The knee-joint straps are duplicated at opposite sides of the leg-members and are made of metal or other durable material. The 85 slip-socket may be made of fiber, leather, rubber, textile material or any suitable material which can be fitted to the stump of the wearer so that the artificial limb may be worn with comfort and ease without 90 chafing or irritating the stump. The socket may be shaped by molding over the stump or a reproduced model of the same. The socket is provided with a shoulder or collar 28, the lower edge of which is adapted to 95 come into contact with the similarly shaped upper edge of the shank member when the weight of the wearer is received by the socket. A strip 30 best shown in Fig. 2 extends over each knee-joint strap 22, and is 100 secured at its ends to the socket so as to form a guide therefor which moves up and down on the knee-joint straps. The strips 30 may be secured to the socket in any suitable manner as by means of screws, rivets, 105 sewing or gluing and one or both ends may be fastened in such manner as to be detachable. The strips 30 may consist of elastic

or non-elastic webbing or of material such as leather, fiber, metal, or any other suitable material. The collar or shoulder member 28 is provided with a projection or raised portion 32 on both sides of the socket, at the rear of the knee-joint straps. This raised portion may be attached by means of rivets, screws, gluing, sewing or other means of attachment, and may consist of an adjustable screw, as shown in Fig. 5, which engages screw threads in the socket member. The projections or members 32 are adapted to be engaged by the upper knee-joint straps when the knee is bent for a sitting position so as to press the socket downward toward the top of the shank member and thus remove the socket from contact with the stump in order to rest the same and prevent chafing and sweating. In order that the projections 32 may be properly engaged, the knee joint straps 20 are preferably provided with lugs 34. The slip socket is provided with means for holding it up to the stump except when released therefrom in the manner just described. This means may consist of an elastic member 36, the lower end of which is provided with a buttonhole 38 for attachment to a button 40 carried by the guide strip 30. In Fig. 2, member 36 is shown detached from the button 40 for clearness of illustration. The upper end of the member 36 is preferably provided with two or more button holes 42 for attachment to a button 44 carried by the upper leg member or by the upper knee-joint strap 20. The provision of more than one button hole 42 provides a convenient manner of adjustment which may be effected in other ways as by a buckle. Fig. 5 shows means for suspending the slip socket from the top of the shank member. Elastic or spring members 46 are attached at their upper ends to the top of the shank member at 48 and these elastic members are attached at their lower ends to the lower portion of the slip socket at 50. The elastic members extend between the shank member and the slip socket and draw the latter upwardly upon the stump of the wearer except when the slip socket is depressed by the knee being bent for a sitting position in the manner previously described. There may be one of the elastic or spring members 46 at the front and one at the rear of the shank and also one at each side. When used at the sides, said members are preferably attached at their upper ends to the knee-joint straps. A check or hold-back, 52, preferable of webbing, is provided for preventing the shank from swinging too far forward relatively to the thigh member. This check extends between the lower rear portion of the lacer or upper leg member and is attached in any suitable manner. The lower portion of the check is preferably provided with a lacing

53 for adjusting purposes. The limb may be supported from the shoulder of the wearer by means of suspenders extending to the front part of the shank and fastened thereto by means of a suitable fastener 54 at each side of the shank. The fasteners 54 are preferably constructed as shown in Fig. 7 and are composed of metal or other suitable material shaped to form a fastener having a base portion to rest upon the material to which they are attached and having a head adjacent the base but separated therefrom by a circumferential groove. The fasteners have a hole extending centrally therethrough to receive a rivet having a head 56 which prevents the rivets pulling out of the material constituting the limb. A blow on the outer end of the rivet serves to secure the fasteners in place after they have been properly positioned upon the limb members. 80 The suspenders referred to may be made of webbing, leather, elastic or textile material, or any combination thereof. As shown in Figs. 2, 6 and 7, the suspenders have an elastic portion 58 provided with a loop 60 at its lower end through which extends the intermediate portion of a cord 62, the ends of which are attached to fasteners 54 by means of eyes or hooks. As a desirable manner of making the attachment to the fasteners 54, I have shown adjustable spring hooks 64, which are preferably covered with leather, rubber, textile material or other material which will deaden metallic sounds that would otherwise occur. A ferrule 66 made of metal, leather, fiber, or other substantial material is provided and each end of the cord 62 is pushed into one of these ferrules and secured by gluing or other suitable means of fastening. The outer end of the ferrule is provided with a hole to receive the shank portion 68 of the hook which may be screwed or driven into the end of the cord surrounded by the ferrule. A shoulder 70 on the hook engages the end of the ferrule and prevents the shank portion thereof from being driven or screwed too far into the end of the cord which is surrounded by the ferrule. The contacting ends of the ferrule 66 and the shoulder 70 may be provided with corrugations and ridges which engage and prevent the hook from readily unscrewing. 110

Figs. 8 to 11 show a short limb member consisting of a fiber shank 72, having portions removed at the front and back, beginning at the point 74 as indicated in Fig. 8 so as to leave side portions which are reinforced by strips 76 of durable material at each side, these strips having a breaking characteristic which is different from that of the fiber. A socket member 78 consisting of suitable material, preferably leather, is secured to the remaining side portions of the shank which have the reinforcing strips 76, 130

and this socket member is covered with suitable material 80 both inside and out in order to give a smooth finish. The rear upper portion of the socket has an opening 82 as best shown in Fig. 9 and through holes at 5 each side of this opening is passed a lacing 84 for the purpose of adjusting the socket to make it larger or smaller to suit the conditions of the stump. In addition to this 10 lacing, there is preferably a strap and buckle device 86 for holding the two sides whereby the parts will be held together in case the lacing should break. A flap 88 of leather or other suitable material is placed inside the 15 opening 82 to protect the stump for the full length of the lacing and this flap extends over the top of the socket and covers the strap and buckle on the outside to prevent irritation of the limb and wear upon the clothing. This flap is preferably fastened on the inside at its lower portion and the out-turned upper end is fastened by the 20 lacing as shown or by any other suitable means. Side straps 90 connect the shank to the ankle bolt shell so that the ankle is reinforced at its weakest portion. The side straps may be attached by threading the inner surface of the customary ankle shell or cylinder to receive screw bolts 92. A band 25 94 may be provided to encircle the thigh of the wearer and a cord 62 similar to that previously described may be attached to the customary suspender.

Figs. 12 and 13 show a desirable form of 30 ankle joint construction in which a sleeve 96 is employed for attaching a foot member 98 to the lower end of the shank member 14. This sleeve is provided with a flat reinforcing plate 100 somewhat above its lower end, and with a reinforcing member 102 at its 35 lower end which may be enlarged at the sides to form bosses or thickened portions 103. A pivotal reinforcing member 104 may also be provided. The lower reinforcing member 102 has a curved portion which 40 forms a seat for the ankle-pivoting member 106, which may be of the usual construction. The reinforcing members carry a socket in 45 which is inserted a buffer 108 the lower end of which engages the top of the foot member, and the reinforcing members also carry 50 a socket which is in alinement with a socket in the foot member. A coil spring 110 is placed in these sockets and a resilient core 55 112, which is shown broken away at its lower end in Fig. 12, is placed within the coils of the spring. The spring on account of engagement with the resilient core, which cushions the coils as shown in Fig. 15, is 60 prevented from sudden shock which might break one of the coils thereof. A buffer 114 is provided between the top of the foot member and the lower end of the sleeve in front of the pivotal connection. In order 65 that the sleeve may be readily inserted with-

in the lower end of the shank member 14 the sleeve may be provided with one or more indentations adapted to be forced outwardly after insertion of the sleeve. A convenient manner of providing for such an indentation is shown in Figs. 12 and 13 in which the numeral 116 designates cuts or slits made in the wall of the sleeve immediately above the upper edge of the plate or ledge 100. A slit of this kind may be made either at 70 one or both sides of the sleeve adjacent the ledge 100, these slits being also adjacent the upper edge of an exterior ledge 101 upon which the lower end of the shank member rests. On account of the cut or slit it is 75 an easy matter to indent the material above the same as indicated in dotted lines at 118 in Fig. 13, which is a plan view of the sleeve looking at the same from the top. The material above the slit may be indented without 80 distorting or changing the sleeve below the slit. After the upper end of the sleeve has been inserted in the lower end of the shank member these two members may be 85 readily secured together by forcing the indented portion outwardly against the inner wall of the shank member. In this manner a standard sleeve may be used for shank members which are of different sizes at their lower ends. By making the cut adjacent the 90 upper edge of the plate 100 it will be apparent that even when the lower end of the shank member is of such size that the indentation is not restored completely to its original position there will be no downward 95 opening into the interior of the sleeve since the plate 100 forms a closure at the bottom of the indentation. Fig. 12 shows that the sleeve 96 may, if desired, be additionally secured within the lower portion of the shank 100 member by rivets. Before the sleeve is secured in place it may be turned toward the right or left to properly position the foot member relatively to the shank member.

Figs. 12 and 14 show a pivot-toe construction for permitting the toe portion to move upwardly when the weight of the wearer is placed thereon. Fig. 12 shows this construction in longitudinal section and Fig. 14 is a top plan view showing the toe portion 110 detached from the foot portion. The foot portion is provided with a forwardly-extending hinge member 120 and the toe portion 122 is provided with two rearwardly-extending hinge members 124 which fit upon the ends 115 of the hinge member 120 so that longitudinal holes through these hinge members are brought into alinement to receive a pintle 126. The toe portion and the foot member are provided at the bottom with adjacent 120 recesses to receive a piece of leather or other suitable flexible material 128, and at the top are cut away to provide an opening across 125 which extends one or more resilient members 130 the ends of which are secured in re- 130

cesses 132 and 134 contained in the toe portion and foot member respectively. The opening above the resilient member 130 is closed by a piece of flexible material 135.

5 The hinge members 120 and 124 are located as closely as practical to the bottom of the foot member for a two-fold purpose. First, the stretching of the leather 128 is reduced to a minimum when the toe portion moves 10 relatively upward, and, second, when this movement occurs the action of the resilient member, which restores the toe portion to original position, is rendered more effective.

I claim:

15 1. An artificial limb comprising a shank member, a slip socket, means for supporting said socket for vertical movement in the upper end of said shank member, knee joint straps secured to said shank member, and 20 transverse strips attached to said socket, said strips passing over said knee joint straps whereby said socket is guided.

25 2. An artificial limb comprising a shank member, a slip socket, means for supporting said socket for vertical movement in the upper end of said shank member, a collar around the upper portion of said socket, the lower edge of said collar being shaped to correspond to the shape of the top edge of 30 said shank member and rest thereon when said socket is depressed, knee joint straps secured to said shank member, and transverse strips attached to said collar, said strips passing over said knee joint straps 35 whereby said socket is guided.

3. An artificial limb comprising a shank member, a slip socket adapted to move up and down in the upper end of said shank member, means for holding said socket in 40 engagement with the stump of the wearer when walking or standing, and means for forcing said socket out of engagement with the stump when the knee is bent for sitting position.

45 4. An artificial limb comprising a shank member, a slip socket adapted to move up and down in the upper end of said shank member, means for holding said socket in engagement with the stump of the wearer 50 when walking or standing, a thigh member, upper knee joint straps attached to said thigh member, lower knee joint straps attached to said shank member, said upper and lower straps being pivoted together, adjustable projections on the upper portion of 55 said socket, and lugs on said upper straps for engaging said projections for forcing said socket out of engagement with the stump when the knee is bent for a sitting 60 position.

65 5. An artificial limb comprising a shank member, a slip socket adapted to move up and down in the upper end of said shank member, knee joint straps secured to said shank member, strips attached to said

socket, said strips passing over said knee joint straps whereby said socket is guided, a thigh member, and elastic members attached at their lower ends to said strips, said elastic members extending up to said 70 thigh member.

6. An artificial limb comprising a shank member, a slip socket adapted to move up and down in the upper end of said shank member, lower knee joint straps secured to 75 said shank member, strips attached to said socket, said strips passing over said knee joint straps whereby said socket is guided, a thigh member, upper knee joint straps secured to said thigh member and pivoted 80 to said lower straps, elastic members, means for attaching the lower ends of said elastic members to said strips, and means for adjustably attaching the upper ends of said elastic members to said upper knee joint 85 straps.

7. An artificial limb comprising a shank member, a thigh member, connections for supporting said shank member from said thigh member, a flat flexible check member 90 secured at its upper end to the rear of said thigh member and extending below the upper end of said shank member, and a lacing positioned entirely below the upper end of said shank member for securing the lower end of 95 said check member to the rear of said shank member, whereby the lacing is prevented from getting between said shank member and the stump of the wearer.

8. An artificial limb comprising a shank 100 member and a foot member pivoted together to form an ankle joint, said shank member having a downwardly opening socket and said foot member having an upwardly opening socket, a coiled spring extending from the closed end of one socket to the closed end of the other socket, and a resilient core with which the coils of said spring engage.

9. An artificial limb comprising a hollow 110 shank member and a foot member pivoted together to form an ankle joint, a sleeve fitted to the lower end of said shank member, said sleeve having a downwardly opening socket and said foot member having an upwardly 115 opening socket, a coiled spring extending from the closed end of one socket to the closed end of the other socket, and a resilient core with which the coils of said spring engage.

10. An artificial limb comprising a hollow shank member and a foot member pivoted together to form an ankle joint, a sleeve fitted to the lower end of said shank member, reinforcing members secured within 125 said sleeve, said members carrying a downwardly opening socket and said foot member having an upwardly opening socket, a coiled spring extending from the closed end of one socket to the closed end of the other 130

- socket, and a resilient core with which the coils of said spring engage.
11. An artificial limb comprising a hollow shank member, a sleeve fitted to the lower end of said shank member, reinforcing partition members secured within said sleeve, an ankle joint member having a seat upon the lower one of said reinforcing members, and a foot member attached to said ankle joint member.
12. An artificial limb comprising a hollow shank member, a sleeve fitted to the lower end of said shank member, thickened portions on the sides of said sleeve, an ankle joint member having a seat upon said thickened portions and a foot member attached to said ankle joint member.
13. An artificial limb comprising a shank member, a foot member, a sleeve member provided with an indentation adapted to be expanded into engagement with the inner wall of said shank member at its lower end, and a pivotal connection between said sleeve member and said foot member.
14. An artificial limb comprising a shank member, a foot member, a sleeve member, a ledge on the inner wall of said sleeve member, said sleeve member being provided with a cut adjacent the upper edge of said ledge whereby the material above the latter may be indented to permit insertion into the lower end of said shank member, said indented material being adapted to be expanded into engagement with said shank member, and a pivotal connection between said sleeve member and said foot member.
15. An artificial limb comprising a shank member, a foot member, a sleeve member, ledges on the inner and outer walls of said sleeve member, said outer ledge being adapted to contact with the lower end of said shank member and said sleeve being provided with a cut adjacent the upper edges of said ledges whereby the material above the latter may be indented to permit insertion into the lower end of said shank member, said indented material being adapted to be expanded into engagement with said shank member, and a pivotal connection between said sleeve member and said foot member.
16. An artificial limb comprising a hollow shell member, a connecting cord extending from said shell member, a spring hook secured to one end of said cord, a fastener secured to said shell member, said fastener having a groove around its head for attachment of said spring hook and having a base portion to rest upon and reinforce said shell member where said fastener is attached.
17. An artificial limb comprising a hollow shell member, a connecting cord extending from said shell member, a ferrule secured to one end of said cord, a spring hook having a shank portion anchored in the material surrounded by said ferrule, a fastener secured to said shell member, said fastener having a groove around its head for attachment of said spring hook and having a base portion to rest upon and reinforce said shell member where said fastener is attached.
18. An artificial limb comprising a hollow hard fiber shell member extending substantially to the top of the limb and having portions removed at the front and rear thereof, reinforcing strips secured at the sides of said member, said strips having a breaking characteristic which is different from that of said member, and a socket member secured to the portions of said shell member which are provided with said reinforcing strips.
19. An artificial limb comprising a hollow hard fiber shell member extending substantially to the top of the limb and having portions removed at the front and rear thereof, reinforcing strips secured at the sides of said member, said strips having a breaking characteristic which is different from that of said member, a socket member secured to the portions of said shell member which are provided with said reinforcing strips, said socket member having an opening at the rear thereof, and means for adjustably holding together the edges of said opening.
20. An artificial limb comprising a hollow hard fiber shell member extending substantially to the top of the limb and having portions removed at the front and rear thereof, reinforcing strips secured at the sides of said member, said strips having a breaking characteristic which is different from that of said member, a socket member secured to the portions of said shank member which are provided with said reinforcing strips, a foot member pivoted to said shank member, side straps secured to said shank member and extending from said foot member part way up said shank member, and securing bolts extending through holes in the lower ends of said side straps.

In testimony whereof I hereunto affix my signature.

OSCAR E. WORMAN.
